LIQUID SEAL TRAP

Keith M. Adair, Eugene, Oreg.

Application June 5, 1950, Serial No. 166,163

2 Claims. (Cl. 220—85)

1

This invention relates to liquid traps and seals, and is an improvement over the construction embodied in my co-pending application Serial No. 57,304, filed October 29, 1948, for Two Way Seal Liquid Trap, now Patent No. 2,605,015.

An object of this invention is to provide an improved seal by employing baffles, a sump, drain plugs, lightening holes, and an outside vent and an outside overflow tube, all of which will be described in the following objects and in the description and attached drawings.

Another object of this invention is to provide vertical and horizontal baffles in the several chambers of a container venting a tank, which baffles will effectively obstruct the free movement of the sealing liquid in the several chambers, thereby eliminating excessive surging and bubbling of the seal fluid during the venting operation or otherwise.

A further object of this invention is to provide a sump into which the overflow leveling tube from the bottom chamber of my invention extends. This sump may be attached to either the bottom wall of the seal unit itself, or to the overflow leveling tube. Excessive seal fluid or excessive tank contents, where the tank to which the seal unit is attached has been overfilled causing the contents thereof to run through the vent and then through the seal unit, will be discharged into this sump.

A further object of this invention is to provide a sump which will contain a seal fluid into which fluid the overflow leveling tube from the bottom chamber of the unit will extend downwardly, thereby sealing this tube from the atmosphere.

Another object of my invention is to provide a sump equipped with an overflow means through which means excess fluid and excess tank contents discharged into the sump may be in turn discharged from the sump either into the atmosphere, or into a tank separate and distinct from the tank being vented. The discharge of such fluid from the sump will in no way affect the operation of the unit to which it is attached.

Another object of my invention is to provide a means through the use of lightening holes whereby the outside air would have free access to the interior of the entire unit, with the exception of the vacuum-pressure chamber, and the circulation of such air would eliminate any possibility of an explosion within the unit, though it might be possible for combustion to take place within the unit. Also such holes may be covered with wire screen to keep out insects, foreign particles or the like.

2

Another object is to provide an air vent tube and an overflow leveling tube that might be used on the outside of the unit to connect the upper chamber with the lower chamber thereof.

5 A further object of my invention is to provide adequate drains and flushing plugs for the several chambers and for the sump. And an object of this invention is to provide a device that has no moving parts, is inexpensive to manufacture and is easy to maintain.

With the above and other objects in view, my invention consists in the arrangement, combination and details of construction disclosed in the drawings and specifications, and then more particularly pointed out in the appended claims.

In the drawing:

The single figure is a vertical section of a liquid trap and seal constructed according to an embodiment of this invention.

20 Referring now to the drawing, there is disclosed one form of this invention. A housing generally designated as 145 is provided in the top wall 146 thereof with a nipple or intake connection 147 whereby the housing 145 may be connected to a tank, reservoir, or the like. The housing 145 includes a cylindrical side wall 148 and a bottom wall 149. An inner horizontal bottom wall 150 is disposed between the top and bottom walls 146 and 149, respectively, and divides the interior of the housing 145 into upper and lower chambers generally designated as 151 and 152, respectively. The upper chamber 151 is divided into a pair of outer chambers 153 and 154 by means of a cylindrical partition 155 which is formed adjacent the lower portion thereof with

30 openings 156 and is formed at the bottom thereof with lugs 157 providing spaces 157a communicating chamber 153 with chamber 154. Lugs 158 are carried by the upper end of the partition 155, engage against the inner side of the top wall 146, and form spaces 158a for communicating the upper portions of chambers 153 and 154. Openings 156 in wall 155 may be in rows or series of rows.

35 A cylindrical member 160 is secured partly within the housing 145 and projects thereabove being formed of a cylindrical side wall 161 which extends through the top wall 146 and engages at its lower end on the inner wall 150. The side wall 161 is formed with lugs 162 at its lower end which engage on the upper side of the inner wall 150 and providing spaces 162a communicating chamber 154 with chamber 166.

40 45 50 55 A cylindrical member 160 is secured partly within the housing 145 and projects thereabove being formed of a cylindrical side wall 161 which extends through the top wall 146 and engages at its lower end on the inner wall 150. The side wall 161 is formed with lugs 162 at its lower end which engage on the upper side of the inner wall 150 and providing spaces 162a communicating chamber 154 with chamber 166.

That portion of cylindrical side wall 161 which is contained within housing 145 forms the inner wall of a vacuum pressure chamber, which vacu-

um pressure chamber includes chambers 153 and 154; said vacuum pressure chamber communicates with inner chamber 166 through openings 163a in the lower portion of cylindrical side wall 161 and through the spaces 162a between the legs or lugs 162 in the bottom of cylindrical side wall 161.

An inner cylindrical member 163 is disposed within the cylindrical member 161 and is formed at its lower end with lugs 164 forming spaces 164a whereby communication will be had between the inner chamber 165 disposed within the cylindrical member 163, and the outer inner chamber 166 which is formed between the cylindrical member 163 and the cylindrical side wall 161. Openings 163a are formed in the lower portion of cylindrical member 161 for communicating the lower portion of chamber 154 with chamber 166. Openings 163a may be in rows or series of rows. The inner member 163 is formed with a plurality of openings 167 extending for a substantial portion of the length of member 163 and is formed at its upper end with lugs 220 forming spaces 221 communicating the upper ends of chambers 165 and 166. The side wall 161 has secured to the upper end thereof a top wall 168 and an upwardly projecting nipple 169 is disposed centrally of the top wall 168. The side wall 161 is provided adjacent the upper end thereof with openings 170, so that atmospheric air may freely circulate through the upper portion of housing 160, and a screen or filtering member 171 is disposed across each opening 170 so as to prevent foreign matter or other material from entering the interior of the inner chamber member 160. Chambers 153 and 154 form the vacuum pressure chamber.

A downwardly flared or conical shield 172 is secured to the upper portion of side wall 161 and engages over the openings 170 so that water or the like will not be blown or drained into the openings 170. A pipe 173 is connected at one end to the vent nipple 169 and extends downwardly and is connected to the side wall 148 of the housing 145 at a point slightly below the inner wall 150. An overflow pipe 174 extends through the inner wall 150 being positioned centrally of the inner wall 163 and defines a liquid level 175 in chambers 165 and 166. The pipe 174 extends downwardly into the lower chamber 152 and terminates at a point closely adjacent the bottom wall 149 of housing 145. A liquid leveling pipe 176 is disposed exteriorly of the side wall 148 of housing 145 and communicates with chamber 151 at a point coplanar with the liquid level 177 defined by the dot and dash line in chamber 151.

The pipe 176 is formed with a U-shaped lower end 178 having the inner side 179 thereof extending upwardly and through the bottom wall 149. Liquids overflowing from chamber 151 will flow downwardly through pipe 176 and then upwardly into the lower portion of chamber 152. An overflow or liquid level determining pipe 180 extends through bottom wall 149 into chamber 152 and is secured to a sump generally designated as 181. The pipe 180 extends through the top wall 182 of sump 181 and terminates at its lower end at a point closely adjacent the bottom wall 183 of sump 181.

The cylindrical side wall 184 of sump 181 is formed with a vent or outlet opening 185 which determines the liquid level 186 indicated by the dot and dash line 186 in sump 181. The upper end of pipe 180 determines the liquid level in

lower chamber 152 which is indicated by the dot and dash line 187. A drain plug 188 is secured in bottom wall 149, and a second plug 189 is secured in side wall 148 in the lower portion of chamber 153 for flushing the chambers above wall 150. A drain plug 190 is secured in bottom wall 183, and a drain plug 191 is mounted in the bight of U-shaped member 178.

Outer chamber 153 has disposed therein a pair of spaced perforate baffles 192 and 193 which are secured about the partition 155, and chamber 154 has disposed therein a pair of spaced perforate baffles 194 and 195 which are coplanar with baffles 192 and 193, respectively. An upper pair of perforate baffles 196 and 197 are disposed within chamber 154 at a point above the liquid level 177 and a filtering medium 198 such as steel wool or the like is disposed between the upper pair of baffles 196 and 197. A lower perforate baffle 199 is disposed within chamber 166 being fixed to outer side wall 161 and positioned closely adjacent the liquid level 177. A second perforate baffle 200 is fixed to side wall 161 above baffle 199 at a point substantially coplanar with top wall 146. A perforate baffle 201 is fixed within side wall 161 above baffle 200, and another perforate baffle 202 is fixed within side wall 161 above baffle 201. An upper pair of perforate baffles or plates 203 and 204 are disposed in the upper portion of chamber 166, and a filtering medium 205 such as steel wool or the like is disposed between the two baffles or plates 203 and 204.

Inner cylindrical wall 163 is formed with openings 206 at a point above the upper baffle 204 so that the atmospheric air can circulate through the upper portion of housing 160.

The side wall 148 is formed with openings 207 at a point above the liquid level 187 and a screen 208 is secured across each opening 207. A conical or flared member 209 is secured to the outer side wall 148 extending partly across the openings 207 so as to prevent water from flowing into the lower chamber 152 through the screened openings 207. The sump 181 is provided with openings 210 at points above the liquid level 186 which are covered by screens 210a, and a conical deflector 211 is secured to the sump 181 about the openings 210. Openings 207 allow free circulation of atmospheric air through the upper portion of lower chamber 152. Openings 210 allow free circulation of atmospheric air through the upper portion of sump 181.

The housing 145 has a plug 212 threaded thereinto at a point above the liquid level in chamber 152 so that the chamber 152 can be flushed or separately filled. A pair of perforate baffles 213 and 214 are disposed in spaced apart relation in lower chamber 152 below the liquid level 187, and a pair of perforate baffles 215 and 216 are disposed in the sump 181 below the liquid level 186.

The inner cylindrical wall 163 has secured therein a lower perforate baffle 217, an upper perforate baffle 218, and an intermediate perforate baffle 219. The baffles in the several chambers of this liquid seal are provided so as to disperse or filter any bubbles which may occur in the liquid seal, and thereby prevent undue rise or fall of the sealing liquid.

Housing 160 has a filler plug 222 in the top wall 166 so that a sealing or flushing liquid may be discharged into housings 145 and 160, and sump 181 has a plug 223 threaded into the top wall 182

thereof so that a flushing liquid may be discharged into the sump.

In the use and operation of this trap, the housing 145 has the nipple 147 connected with the vent of the tank and housing 145 will be disposed in a vertical position. Chambers 151 and 152 are filled with the desired liquid to the levels indicated at 177 and 187, respectively, the filling being accomplished by removing the filler plug 222 in housing 160. Liquid is discharged into housing 160 until the liquid flows out of opening 185 in sump 181.

Assuming that the tank is being filled, the air pressure in the tank will be relieved through vent 141, and at this time the level 177 of liquid in chamber 151 will be lowered by pressure in chamber 151, and the liquid level in housing 160 will rise. The liquid level in housing 160 may rise to the level 175 and any further rise of liquid in housing 160 will cause the liquid to overflow into pipe and run down into lower chamber 152. The exhaust of air from housing 160 will occur through openings 170 and vent 169.

Inasmuch as the size or volume of the main tank is relatively large as compared to the trap, any rapid filling or draining of the main tank will cause a relatively large outflow or inflow of air through the trap. The baffles 192 and 193 in outer chamber 153 prevent undue surging of the sealing liquid in chamber, and the baffles 194 and 195 prevent surging of the liquid in chamber 154. In like manner the baffles in housing 160 and within perforate member 163 prevent surging of the liquid in housing 160. The air escaping from the tank will tend to cause bubbling in the seal liquid and the baffles will act to break up the bubbles.

Assuming that the main tank is being emptied or predetermined quantities of liquid are being taken therefrom, as the liquid level in the tank drops a partial vacuum will be created, and the liquid level 177 will rise in chambers 151 and 153 with air passing downwardly through housing 160, through openings 163a and 164a and bubbling up through baffles 192 and 193. As the liquid rises in chamber 153 above level 177, the liquid will drain downwardly through pipe 176 into lower chamber, and any overflow in chamber 152 will drain through pipe 180 to sump 181. The baffles 213 and 214 in chamber 152 prevent undue surging of the incoming liquid so that the liquid will not spill out through the screened openings 207.

I do not mean to confine myself to the exact details of construction herein disclosed, but claim all variations falling within the purview of the appended claims.

What I claim is:

1. A liquid sealing device for attachment to the vent of a tank comprising a housing having side, top and bottom walls, means carried by said top wall for connecting said housing to said vent, an inner horizontal wall dividing said housing into upper and lower chambers, an overflow pipe connecting said upper chamber with said lower chamber, a vacuum housing disposed partly in said upper chamber and partly above said top wall, said vacuum housing communicating at its lower portion with said upper chamber, a vent

nipple extending from the upper closed end of said vacuum housing, a pipe connecting the upper portion of said lower chamber with said nipple, a perforate cylindrical partition in said vacuum housing, a centrally disposed vertical pipe projecting through said inner wall and terminating at its upper end adjacent the upper portion of said vacuum housing, said vertical pipe terminating at its lower end in the lower portion of said lower chamber, a perforate cylindrical partition in said vacuum housing about said vertical pipe, vertically spaced apart baffles about said partition, vertically spaced apart baffles interiorly of said partition, a cylindrical perforate partition in said upper chamber, a pair of perforate baffles about said second named partition, a second pair of perforate baffles interiorly of said second partition, a third pair of perforate baffles interiorly of said second partition and disposed above said second pair of baffles, a filtering means between said third pair of baffles, a pair of perforate upper baffles in the upper portion of said vacuum housing, a filtering means between said upper pair of baffles, a sump below said first housing, a pipe connecting said lower chamber with said sump, said sump having an overflow opening in the side wall thereof, spaced perforate baffles in said sump, screened openings in the upper portion of said first housing, a conical shield carried by said first housing about said openings, screened openings in the upper portion of said vacuum housing, a second conical shield carried by said vacuum housing about said latter named openings, screened openings in the upper portion of said sump, and a third conical shield carried by said sump about the screened openings in said sump.

2. A liquid sealing device for attachment to the vent of a tank comprising a housing having a cylindrical side wall, top and bottom walls, means carried by said top wall for connecting said housing to said vent, an inner horizontal wall dividing said housing into upper and lower chambers, a vacuum housing disposed partly in said upper chamber and partly above said top wall, an overflow pipe extending from the upper portion of said vacuum housing into said lower chamber, a second overflow pipe communicating the upper portion of said upper chamber with said lower chamber, a sump below said first-named housing, a third overflow pipe connected between said lower chamber and said sump, means venting said lower chamber and said vacuum housing, perforate baffles in said upper chamber, perforate baffles in said vacuum housing, and perforate baffles in said sump, said baffles breaking up the surge of liquid in said first-named housing, said vacuum housing and said sump, said sump having a discharge opening.
